UNITED STATES PATENT OFFICE.

BURTON MALLORY, OF NEW HAVEN, CONNECTICUT.

DESIGN FOR DOOR-KNOBS AND ROSES.

Specification forming part of Design No. 7,378, dated April 14, 1874; application filed March 5, 1874.
[Term of Patent 7 years.]

B.

To all whom it may concern:

Be it known that I, BURTON MALLORY, of New Haven, in the county of New Haven and State of Connecticut, have invented a new Design for Door-Knob and Rose; and I do hereby declare the following, when taken in connection with the accompanying drawings and the letters of reference marked thereon, to be a full, clear, and exact description of the same, and which said drawings constitute part of this specification, and represent, in—

Figure 1 a front view of the rose; Fig. 2, a front view of the knob; and in Fig. 3, a side view of the knob.

This invention relates to a design for door-knob and rose; and consists, first, in the configuration and ornamentation of the rose; second, in the configuration and ornamentation of the knob, all as shown in the accompanying illustration and hereinafter described.

The rose has a circular center, from which three wings extend, two below and one above. The outlines of the lower wings are the same, but reversed, the edge a vine branching from the tip of each up to the raised edge around the center. This vine produces a floriated edge. The edges of the upper wing are formed by a similar vine running up from the edge of the center and terminating in an indented

semicircle. The floriated edge of the wings, combined with the floriated scroll-work around the center, as shown, constitute this part of my design. In circumferential form the knob is round. Its face or front has a raised ring at the center inclosing a star. From this a raised scroll-work radiates, and extends to a bead, *a*, on the edge, the center or star flat and projecting—that is, in longitudinal form the knob is shaped as seen in Fig. 3, a bead, *a*, around the ball, a projecting center, *d*, in front, and similar projections *f* on the rear, as shown.

I claim as my invention—

1. The design for door-knob rose, consisting of the circular center with a raised edge inclosing a tracery of floriated scroll-work and the three wings, the edges of which are a raised floriated vine, as shown and described.

2. The design for the ornamentation of door-knobs, consisting of the round knob with projecting star center and raised scroll-work radiating therefrom to the bead *a* on the edge, as shown and described.

BURTON MALLORY.
